Primary Examiner — Antoine D Davis(74) *Attorney, Agent, or Firm* — Cantor Colburn LLP**CLAIM**

We claim, the ornamental design for a measurement device, as shown and described.

DESCRIPTION

FIG. 1 is a front plan view of a fourth embodiment the invention;

FIG. 2 is a rear plan view of the embodiment of FIG. 1;

FIG. 3 is a first side plan view of the embodiment of FIG. 1;

FIG. 4 is a second side plan view of the embodiment of FIG. 1;

FIG. 5 is a bottom plan view of the embodiment of FIG. 1;

FIG. 6 is a top plan view of the embodiment of FIG. 1;

FIG. 7 is a first perspective view of the embodiment of FIG. 1;

FIG. 8 is a second perspective view of the embodiment of FIG. 1;

FIG. 9 is a third perspective view of the embodiment of FIG. 1; and,

FIG. 10 is an enlarged plan view of the repeating pattern along the arm portions of FIGS. 1-9.

The phantom lines shown in FIG. 1-FIG. 10 are environmental and not part of the claimed design.

The light gray portions shown in FIG. 1-9 have RGB values of R=198, G=198, B=198.

The white portions shown in FIG. 1-9 have RGB values of R=230, G=230, B=230.

The dark gray portions shown in FIG. 1-9 have RGB values of R=056, G=085, B=168.

References to "side", "top", "front", "rear" and "bottom" in the figure descriptions are not meant to require certain in-use orientation; a measurement device according to the claimed design may be used in any orientation.
